UNITED STATES PATENT OFFICE.

HEINRICH DEGENER, OF BERLIN, GERMANY.

MATRIX-SETTING AND LINE-CASTING MACHINE.

982,174.

Specification of Letters Patent. Patented Jan. 17, 1911.

Application filed July 14, 1910. Serial No. 571,935.

To all whom it may concern:

Be it known that I, HEINRICH DEGENER, of 26 Hollmannstrasse, Berlin, German Empire, manager, having invented certain new and useful Improvements in or Relating to 5 Matrix-Setting and Line-Casting Machines, do hereby declare that the following is an exact specification of the same.

This invention relates to an improvement 10 in or modification of the invention described in application Serial No. 482,845 which refers to a matrix setting and line casting machine in which several kinds of matrices are used, and the sorting of the single kinds of 15 type from each other is effected so that the matrices are pushed laterally apart by a railway switch-like device, then taken up by separate recesses by pins, whereupon the single kinds are drawn apart and supplied 20 to suitable distributing bars, and a device has also been already shown in which the receiving pins can be at the same time utilized as sorting bars.

This invention relates to a further development 25 of the invention described in the prior application, according to which the sorting of the matrices is effected already while they are being pushed out of the so-called elevator during the transfer to the 30 rails carrying the matrices to the magazine, the said rails or bars being at the same time utilized as receiving bars.

A construction according to this invention is illustrated in the accompanying drawing 35 in which—

Figure 1 is a front elevation, Fig. 2 a side elevation, partly in section, Fig. 3 a plan and Fig. 4 a side elevation in the position after the receiving bars have already moved 40 slightly upward. Fig. 5 is a front elevation of a part of the machine containing a construction according to this invention and Fig. 6 is a side elevation to Fig. 5. Figs. 7 and 8 are two matrices.

The matrix line consisting of matrices *a* and spacers *b*, is raised in the known manner after the casting of the line, brought to the so-called second elevator and thence pushed in the known manner out of the first elevator 45 on to the second elevator provided with lifting bars *e* and *f*, by which it is brought in the known manner to the distributing bars *r* and *s* (Figs. 5 and 6). The lever *c* of the lifting bars is of the known 50 construction; the front portion of the same

is shown in Figs. 1 and 2, but in place of the lifting bar used in the known constructions, having a triangular cross-section and ribs corresponding to the distributing teeth according to my invention, there is provided a 60 yoke or shackle *d* on which are mounted two lifting bars *e* and *f*. The latter are guided by two bars *g* and are always pressed apart (see Fig. 4) by a spring *h* placed between them on the bar. To the machine frame 65 itself are secured two horns *i* which, during the sinking of the lifting bars *e* and *f* for the purpose of receiving the matrices, into the position shown in Fig. 2, act in front and at the back on the lifting bars *e* and *f* and bring them nearer to each other, the springs 70 *h* being compressed. In that position, as shown in Fig. 2, the matrices are pushed out of the elevator on to the lifting bars. The front end of the lifting bars is provided 75 with a beveled face *k*, in the same manner as the sorting bars in the said prior application, and also the matrices of the different fonts are provided with recesses *o* and *p* respectively as clearly shown in Figs. 7 and 80 8, so that, as will be seen from Fig. 3, the matrices, when being pushed on to the lifting bars, are moved by the said bars entering their recesses away from each other 85 according to the side on which the recesses or notches are situated. By this arrangement the sorting device of the prior application is formed by the one end of the lifting bars.

In order to prevent the spacers *b* which are 90 in the elevator in the position shown in Fig. 1, that is to say with their lateral lugs at a higher level than the upper edge of the matrices, from being also seized by the lifting bars, the spacers are guided from the 95 elevator to their magazine in a broken line, that is to say, they are first guided with their lugs into a downward conduit *m* to such an extent that their upper lugs are lower than the lowest position of the lifting bars, and only then they are guided in a rectilinear conduit *n* toward the space magazine. Thus it is possible to raise the sorted out 100 matrices pushed onto the lifting bars, while leaving the spacers in their place in order 105 to enable them to be guided from here into the space magazine without alteration.

After the matrices have been transferred to the lifting bars, the lever *c* is again 110 raised in the known manner, and the two

bars, being released by the horns *i*, will be pushed apart by the springs *h* and brought into the position shown in Fig. 4. The lifting bars with the matrices thus pushed apart, 5 arrive in front of the distributing bars proper *r* and *s* (Figs. 5, 6), and the matrices can then be pushed on the latter for the purpose of distributing them among the various magazines. This arrangement is an improvement 10 on the arrangement described in the prior application, as it is now no longer necessary to insert in front of the distributing bars proper the railway switch-like device for sorting the matrices. In that way 15 space is economized, and moreover, the double movement of the slide pushing the matrices from the lifting bars first through the sorting mechanism and, after the pulling apart, on to the distributing bars, which 20 movement takes up a great deal of time, is avoided.

Having now particularly described and ascertained the nature of my invention and in what manner the same is to be performed, 25 I declare that what I claim is:

1. In a matrix setting and line casting machine in combination several fonts of matrices each font being provided with recesses, a lifting device bringing the matrix 30 line to the distributing mechanism and containing lifting bars upon which the matrix line is pushed, one lifting bar for each font of matrices and a sorting device engaging with the matrix recesses and dividing the 35 matrix line into different fonts while being pushed onto the lifting bars.

2. In a matrix setting and line casting machine in combination several fonts of matrices each font being provided with recesses, a lifting device bringing the matrix 40 line to the distributing mechanism and containing lifting bars, one for each font of matrices provided at one end with a sorting device engaging with the matrix recesses and dividing the matrix line into 45 different fonts.

3. In a matrix setting and line casting machine in combination several fonts of matrices each font being provided with recesses, a lifting device bringing the matrix 50 line to the distributing mechanism and containing lifting bars, one for each font of matrices provided at one end with a sorting device engaging with the matrix recesses and dividing the matrix line into different 55 fonts and means for automatically moving the lifting bars from and to each other.

4. In a matrix setting and line casting machine in combination several fonts of matrices each font being provided with recesses, a lifting device adapted to receive the matrix line for the purpose of conveying the same to the distributing mechanism and containing lifting bars, one for 60 each font of matrices provided at one end

with a sorting device engaging with the matrix recesses and dividing the matrix line into different fonts and means for automatically bringing the said lifting bars nearer to each other into the position required for sorting during the sinking to the receiving position. 70

5. In a matrix setting and line casting machine in combination several fonts of matrices each font being provided with recesses, a lifting device adapted to receive the matrix line for the purpose of conveying the same to the distributing mechanism and containing lifting bars, one for each font of matrices provided at one end with a sorting 75 device engaging with the matrix recesses and dividing the matrix line into different fonts, means for automatically bringing the said lifting bars nearer to each other into the position required for sorting during the sinking to the receiving position and means for moving them apart during the upward movement. 80

6. In a matrix setting and line casting machine in combination several fonts of matrices each font being provided with recesses, a lifting device bringing the matrix line to the distributing mechanism and containing lifting bars which descend to receive the matrix line, one lifting bar for 90 each font of matrices provided at one end with a sorting device engaging with the matrix recesses and dividing the matrix line into different fonts, horns arranged on the frame of the machine acting on the descending 95 lifting bars and bringing them nearer to each other and means for moving them apart. 100

7. In a matrix setting and line casting machine in combination several fonts of matrices each font being provided with recesses, a lifting device bringing the matrix line to the distributing mechanism and containing lifting bars which descend to receive the matrix line, one lifting bar for each 105 font of matrices provided at one end with a sorting device engaging with the matrix recesses and dividing the matrix line into different fonts, horns arranged on the frame of the machine acting on the descending 110 lifting bars and bringing them nearer to each other and springs moving them away from each other during the rising of the lifting device. 115

8. In a matrix setting and line casting 120 machine in combination a matrix line consisting of spacers having lugs and matrices, said matrices having recesses, a lifting device to which the matrix line is transferred, said lifting device containing lifting bars 125 engaging the matrix recesses and means for guiding the spacers during the transfer of the line to the lifting device to carry their lugs beneath the lifting bars.

9. In a matrix setting and line casting 130

machine in combination a matrix line consisting of spacers having lugs and matrices, said matrices having recesses, a lifting device to which the matrix line is transferred, said lifting device containing lifting bars engaging the matrix recesses and a guide way for guiding the spacers during the transfer of the line to the lifting device downward until their lugs are below the

lifting bars, so that the matrices can be freely removed from the line upward.

In witness whereof I have hereunder set my hand in presence of two witnesses.

HEINRICH DEGENER.
